(57) **CLAIM**

The ornamental design for a LED lamp and head section thereof, as shown and described.

DESCRIPTION

FIG. 1 is a first perspective view of a LED lamp and head section thereof according to a first embodiment of our invention.

FIG. 2 is a second perspective view of the LED lamp and head section thereof of FIG. 1.

FIG. 3 is a right side view of the LED lamp and head section thereof of FIG. 1, a left side view being a mirror image thereof.

FIG. 4 is a third perspective view of the LED lamp and head section thereof of FIG. 1.

FIG. 5 is a top view of the LED lamp and head section thereof of FIG. 1.

FIG. 6 is a front view of the LED lamp and head section thereof of FIG. 1.

FIG. 7 is a rear view of the LED lamp and head section thereof of FIG. 1.

FIG. 8 is a perspective view of the head section of the LED lamp and head section thereof of FIG. 1.

FIG. 9 is a front view of a LED lamp and head section thereof according to a second embodiment of our invention.

FIG. 10 is a front view of a LED lamp and head section thereof according to a third embodiment of our invention.

FIG. 11 is a front view of a LED lamp and head section thereof according to a fourth embodiment of our invention.

FIG. 12 is a front view of a LED lamp and head section thereof according to a fifth embodiment of our invention.

FIG. 13 is a front view of a LED lamp and head section thereof according to a sixth embodiment of our invention.

FIG. 14 is a front view of a LED lamp and head section thereof according to a seventh embodiment of our invention.

FIG. 15 is a front view of a LED lamp and head section thereof according to a eighth embodiment of our invention.

FIG. 16 is a front view of a LED lamp and head section thereof according to a ninth embodiment of our invention; and,

FIG. 17 is a front view of a LED lamp and head section thereof according to a tenth embodiment of our invention.
